UNITED STATES PATENT OFFICE.

HENRY M. LANE, OF DETROIT, MICHIGAN.

LADLE CRANE.

Application filed January 7, 1926. Serial No. 79,855.

This invention relates to ladle cranes and it comprises a ladle having traversing and elevating means and means for swinging it to afford a desired adjustment across the 5 horizontal line of travel of the crane for positioning the pouring lip during the pouring operation; all as more fully hereinafter set forth and as claimed.

In ladle cranes now in use, the crane carrying the ladle travels in a fixed horizontal line and the ladle may be elevated or lowered in a vertical line, as is shown in my prior Patent No. 1,266,828 of May 21, 1918. While there are certain advantages in this 10 type of construction, it is subject to certain disadvantages particularly when there are gangs of molds or molds arranged in line to be filled. This disadvantage arises through the fact that as the ladle is gradually tilted more and more toward the horizontal as successive molds are poured, the pouring lip or edge of the ladle moves out of alignment with the line of travel of the crane or the line of position of the molds, 15 and while this can be compensated for to some extent by positioning of the molds, it is not always possible since it is not an easy matter to anticipate the degree to which the ladle will be tilted for the pouring of any 20 particular mold.

According to the present invention this disadvantage is overcome by mounting the ladle to make it capable of relative movement either to the right or left of its supporting member so that as the crane travels the ladle can be adjusted in pouring position to compensate for normal displacement which would occur by ordinary tilting.

In the accompanying drawings, I have illustrated an advantageous embodiment of my invention,

In the showing,

Fig. 1 is a side elevation of a crane embodying my invention;

45 Fig. 2 is a section on line 2—2 of Fig. 1; Fig. 3 is a section on line 3—3 of Fig. 1; Fig. 4 is a section on line 4—4 of Fig. 2; Fig. 5 is a diagrammatic plan view of a series of gang molds; and,

50 Fig. 6 is a diagrammatic end view illustrating different positions to which the ladle may be placed when pouring metal.

The trolley frame A is provided with trolley wheels 1 mounted in hangers 2 carried 55 by the frame and adapted to travel upon the overhead rail B. A motor 3 supplies the

power for movement of the trolley wheels 1, while the motor 3' supplies power for movement of the ladle carrying frame.

A supporting beam C is suspended from the trolley frame A by ropes or cables 4 which pass over pulleys 5 and is provided with guide members 6. These guide members 6 are adapted to move vertically in the depending guide members 7 formed on the trolley frame A. Pivotally supported to and positioned beneath the beam C is a ladle carrying frame D. The ladle 8, used in connection with this machine, is provided with trunnions 9 and 10 for the purpose of engaging the arms 11 which are suitably connected to the ladle frame D. The trunnions 10 carry a gear wheel 12 which meshes with a pinion or smaller gear wheel 13 mounted on a shaft 14 carried by the arm 15 on the cage 16. The shaft 14 is journaled in an enlarged bearing 17 in the cage 16 and is provided with a hand wheel 18.

The ladle frame D is pivotally supported to the beam C at 19. The beam C has suitably secured to one side thereof, depending arms 20 provided with rollers 21 on their opposite ends for engaging the under side of the ladle frame D thereby allowing relative easy movement between these two frames. The ladle frame is provided with a rack bar 22 suitably secured to the outer surface thereof which is adapted to engage a worm gear 23. A shaft 24 upon which the pinion is carried is provided at one end with a bevel gear 25 adapted to mesh with the bevel gear 26 carried by the shaft 27. A ball and socket joint 28 connects shaft 27 to the operating shaft 29. Telescopically positioned within the shaft 29 is a shaft 30 connected to the hand wheel 31 whereby movement of the ladle frame D is controlled with respect to the beam C. If desired, the operating shaft 29 may be a single shaft and this is advantageously used with equal success.

The operation of the ladle crane is as follows:

Assuming a gang of molds such as shown in Fig. 6 is to be filled, the crane carrying the ladle is brought into position between the first molds through operation of the traversing mechanism described. By the elevating mechanism the ladle is raised to the required height and tilted to position to pour into the lower left hand mold as shown in Fig. 6. The ladle is then further elevated and through operation of handle 31, shafts

30 and 29 and gears 25 and 26, pinion 23 and rack 22, the ladle is swung to one side of the normal line of travel of the crane so that when it is further tilted for the purpose of 5
6 pouring into the next higher mold to the left, its lip will be directly over the sprue. This operation is repeated for filling the next higher mold in the gang. The ladle may then be positioned in vertical relation 10 and conveyed to the next succeeding series of molds where the operation aforementioned is repeated. After the series of molds have been poured on the one side of the gangway, and it is desired to pour the series 15 on the right side of the ladle, the ladle is brought to vertical position adjacent the lower right hand mold and through the operation of the mechanism aforementioned, the ladle frame is swung to the right so that 20 the lip of the ladle is moved out of the center line of travel thereby affording opportunity for the pouring of the metal into the lower right hand mold, or, of course, after molds on the one side are poured, the ladle 25 may be tilted to pour molds on the opposite side.

What I claim is:—

1. A ladle crane comprising a ladle and a frame, elevating and traversing means therefor and means for swinging said ladle across the horizontal line of travel of the crane. 30
2. A ladle crane comprising a ladle, means for supporting the ladle, means for tilting the ladle, and means for swinging the ladle across the horizontal line of travel of the crane. 35
3. A ladle crane comprising a ladle, ladle supporting means, an operator's cage carried by the crane in fixed relation to the ladle supporting means, means for elevating the ladle supporting means and cage, traversing means for the crane and means operable from the cage for swinging said ladle and supporting means across the horizontal line of travel of the crane. 40
4. A ladle crane comprising a ladle, ladle supporting means, elevating and traversing 45

means, an operator's cage carried by said crane, means operable from said cage for 50 tilting the ladle and swinging the ladle and supporting means transversely of the line of travel of the crane.

5. A ladle crane comprising a trolley frame, a ladle frame, means for elevating the 55 ladle frame in the trolley frame, ladle supporting means carried by the ladle frame, an operator's cage within said ladle frame in fixed relation to said ladle supporting means and means operable from said cage 60 for swinging said ladle and supporting means transversely of the line of travel of the crane.

6. A ladle crane comprising a trolley frame having depending guide members, a 65 member telescopically positioned between said guide members, a ladle frame pivotally supported by said member and means carried by said ladle frame whereby the ladle frame may be swung transversely of the line 70 of travel of the crane.

7. A ladle crane comprising a trolley frame having depending guide members, a transverse member slidable in said guide members, a ladle frame pivotally secured to 75 said transverse member, a rack carried by said ladle frame and means in cooperation with said rack for swinging the ladle frame transversely across the line of travel of the crane. 80

8. A ladle crane comprising a trolley frame having depending guide members, a transverse member slidable in said guide members, a ladle frame positioned beneath said transverse member and pivotally supported thereby, a ladle carried by said ladle frame, means for tilting the ladle, a rack carried by said ladle frame, a pinion engaging said rack, gear members for operating said pinion and means connected to said gear members for controlling the movement thereof for swinging the ladle frame transversely across the line of travel of the crane. 85 90

In testimony whereof, I have hereunto affixed my signature.

HENRY M. LANE.
